Application March 13, 1946, Serial No. 654,065

12 Claims. (Cl. 81—84)

1

The present invention relates to an automatically adjustable wrench having parallel jaws and is a continuation-in-part of my copending application on Wrench, Serial No. 640,047, filed January 9, 1946, now abandoned.

The jaws of any wrench used on nuts and the like must present flat parallel faces and must closely fit the nut to avoid a destructive concentration of load at the corners of the nut when it is turned. In that connection, the load applied at each of two corners of a hexagonal nut for a five-eighths inch bolt by a fifty pound pull at the end of a ten inch wrench is approximately twelve hundred pounds. Higher loads are frequently exerted in actual practice. Such loads concentrated at the corners of a nut crush the corners. These high forces are also applied to the jaws of the wrench and act in a direction to separate them. Consequently, the wrench must have great strength to withstand these high stresses without breaking the wrench or spreading the jaws. While fixed open end wrenches may be made with sufficient strength, they cannot be made to fit the corresponding nut with sufficient accuracy to avoid objectionable concentration of the twisting load at two corners of the nut for the reason that a close fit would make their application to the nut difficult. To make application practical, substantial clearance is specified in the United States Standard for open end wrenches (.006" for a $\frac{5}{8}$ " nut). This necessary clearance is so high that socket wrenches which distribute the load over all corners of the nut are preferred to open end wrenches where it is possible to use them. With either type a separate wrench is required for each size nut, which is exceedingly inconvenient.

Many attempts have been made to devise a satisfactory adjustable wrench in order to avoid the necessity of carrying and selecting the proper one of a multiplicity of wrenches in assembling and repairing machinery. The most widely used adjustable wrenches have a sliding jaw which is adjusted relative to the other jaw by a screw. These may be opened up for easy application and then tightened on the nut before the nut is turned. However, distortions and unavoidable play between the relatively sliding parts permit the jaws to open slightly under load and even a deflection of a few thousandths of an inch is objectionable. In addition, the necessary manipulations of the adjusting screw are troublesome, particularly when the wrench must be used in places which are not within the range of vision of the mechanic. As a result of these defects,

2

fixed wrenches of the socket or open end type are used very extensively in preference to adjustable wrenches.

Many other forms of adjustable wrenches have been devised. Some have been automatically adjustable but are usable only as pipe wrenches because they do not maintain the jaws in parallelism.

Parallel jaw pliers have been proposed but these generally rely on hand gripping pressure to resist the forces exerted against the jaws. If sufficient force multiplying mechanism is provided for this purpose, as, for example, by a toggle mechanism, the movement of the jaws is insufficient to permit use on more than one size of nut unless an auxiliary adjustment of some kind is also provided. Prior parallel jaw toggle pliers have, moreover, employed parallel linkages which are subject to bending stresses and excessive distortion.

Many of the proposed automatically adjustable wrenches have employed some form of ratchet mechanism for locking the jaws in any one of a plurality of positions. Most of these have been defective because no provision was made for fitting nut sizes intermediate the possible positions of adjustment of the ratchet. In addition, all such wrenches heretofore proposed have been peculiarly subject to spreading, distortion and misalignment or non-parallelism of the jaws under load. Moreover, no prior ratchet type constructions have embodied a ratchet mechanism capable of withstanding the high stresses encountered in the normal use of a wrench. In that connection, it should be noted that in order to carry heavy loads, engagement of a substantial tooth area is required. No one ratchet tooth can carry sufficient load unless it is so large that the increments of adjustment of the wrench are excessive. All prior attempts to distribute the load over a plurality of teeth have involved mechanisms which did not insure engagement to the full tooth depth and distribution of the load on all teeth. Consequently, there is serious danger of stripping or mangling the teeth.

Accordingly, it is one object of the present invention to provide a wrench which will automatically grip a range of different size nuts with less angularity between the jaws and the nut faces than is encountered in standard fixed wrenches.

Another object of the present invention is to provide an adjustable parallel jaw wrench which may by a single convenient manipulation be closed on any size nut within a relatively wide range of sizes and thereafter bring into action

a force multiplying mechanism which will clamp the nut with a very strong clamping force.

Another object is to provide a wrench in which all of the principal loads to which the elements of the wrench are subject are direct tension and compression forces, with the result that distortion is minimized.

Another object of the present invention is to provide a wrench having an improved form and arrangement of ratchet adjusting mechanism in which a load carrying engagement to the full depth of the teeth and over a substantial tooth area is positively insured and in which the teeth are of a form which provides maximum strength.

Another object of the present invention is to provide a wrench having a ratchet adjusting mechanism in combination with means for automatically compensating for the inherent incremental characteristic of the ratchet mechanism so that the wrench will close on and clamp any size nut.

Another object of the invention is to provide a wrench in the form of a pair of toggle acting pliers in which a normal squeezing of the handles toward each other automatically closes the jaws on any size nut and applies a final toggle clamping action.

Another object of the invention is to provide a toggle plier wrench of the type mentioned in which the jaws are maintained in substantial parallelism.

Another object of the invention is to provide a toggle plier wrench in which the final position of the free ends of the handles remains approximately the same regardless of variations in the size of the nut to which it is applied.

Another object of the invention is to provide a wrench of the type mentioned which, by a simple manipulation, may either have self-locking or automatic releasing characteristics.

Other objects, which include the provision of a wrench of the type mentioned which is simple and rugged in construction, will become apparent from the following specification, the accompanying drawings and the appended claims.

In the drawings:

Figure 1 is a side elevation of the preferred form of the invention, with parts broken away and showing the wrench in fully open position;

Figure 2 is a side elevation showing the wrench in its fully closed position;

Figure 3 is a transverse section taken on the line 3—3 of Figure 1;

Figure 4 is a transverse section taken on the line 4—4 of Figure 1;

Figure 5 is a transverse section taken on the line 5—5 of Figure 1;

Figure 6 is a transverse section taken on the line 6—6 of Figure 1;

Figure 7 is a fragmentary enlarged longitudinal section taken on the line 7—7 of Figure 6;

Figure 8 is a greatly enlarged fragmentary, longitudinal section similar to Figure 7 showing the manner in which the ratchet teeth approach each other during operation of the wrench;

Figure 9 shows a modified form of the invention incorporating means for selectively using the wrench as a self-locking clamp; and

Figure 10 is a fragmentary section taken on the line 10—10 of Figure 9.

In its broadest aspect, the principal objects of the present invention are achieved by combining in a parallel jaw wrench a ratchet mechanism and a force multiplying mechanism capable of

clamping the jaws on a nut after they have engaged the nut and after the ratchet mechanism has engaged. This clamping mechanism is capable of giving the jaws a small additional closing movement sufficient to cover the gap between the increments of adjustment of the ratchet mechanism, and has sufficient force multiplying capacity to apply the required jaw gripping force in response to ordinary hand pressure. In order to accomplish that result, the ratchet teeth are made quite small and the load is distributed over a plurality of teeth. Since this provides small increments of adjustment of the ratchet, the clamping mechanism need not transmit any appreciable movement and hence may have the requisite force multiplication. The wrench is so constructed that by a single hand movement in one direction, the normally open jaws are closed on a nut and thereafter the clamping force applied. The ratchet mechanism becomes effective automatically in response to engagement of the nut by the jaws, and the clamping mechanism becomes effective after the ratchet mechanism engages.

In the preferred form of the invention shown in the drawings, the wrench resembles a pair of pliers and the clamping mechanism is a toggle linkage. Thus, as best shown in Figures 1 and 2, the wrench comprises a pair of handles 1 and 2 which are positioned relative to each other in the manner of the handles of a pair of pliers. The handle 2 is preferably formed as a unitary forging with an integrally fixed jaw 3. The handle forging has a centrally located web portion 4 which extends the full length of the handle and a wider flange portion 5, which also extends the full length of the handle 2 and terminates in a U-shaped section 6, shown best in Figure 3. The web portion 4 is provided intermediate its ends with a generally triangular opening 7, which is made of substantial size in order to lighten the tool and which also serves an additional purpose hereinafter mentioned. At the rear of opening 7, the web is further reduced in thickness at 8. The web is also provided with an opening 9 located forwardly of the opening 7 and separated from the latter by an intermediate web portion 10. The forward wall of the opening 9 is formed with a series of ratchet teeth 11 and the opening is generally in the form of an elongated slot extending approximately perpendicular to the face of jaw 3.

Positioned within the opening 9 is a ratchet pawl 12 having a plurality of teeth 13 adapted to mesh with the previously mentioned teeth 11. The pawl 12 is press fitted or otherwise fixedly secured to a pin 14 having a flattened portion 15 adapted to prevent rotation of the pawl relative to the pin.

The wrench is also provided with a movable jaw 16 having a pair of side plates 17 which embrace opposite sides of the web 4 of the handle 2, as best shown in Figure 6. The lowermost extremities of the side plates 17 are provided with suitable openings to receive the ends of the pin 14. These openings in the plates 17 are likewise provided with flat portions, indicated in dotted lines at 18 in Figure 7, adapted to co-operate with the flat surface 15 on the pin 14 to limit rotation of the pin within the openings in the side plates. The space between the flat surfaces 18 of the openings in the side plates 17 and flat 15 on the pin 14 is sufficient only to permit the minute rocking movement of the pawl 12 necessary to maintain full contact between the teeth

11 and 13 during the limited pivotal movement of the jaw 16 relative to the axis of pin 14 incident to operation of the toggle mechanism hereinafter described in greater detail.

The jaw 16 may be made up in any desired manner but, as illustrated, comprises an integral element of generally channel shape with the side plates connected by a web, the inner surface of which is curved in the manner indicated in dotted lines in Figure 1, and merges with the jaw face 19.

The rear end of the web of jaw 16 projects beyond the rear edges of the side plates 17, as best shown in dotted lines at 20 in Figure 1, and is provided with a transverse opening to receive a pivot pin 21. The handle 1 is formed as a stamping having a generally U-shaped cross section providing relatively deep side wall portions 22 which embrace the projecting portion 20 of the jaw 16 and also a substantial portion of the web 4 of the handle 2. The side plates 22 are provided with suitable openings to receive pivot pin 21. The handle comprises one link of a toggle linkage including an additional link 23, which is pivoted between the side wall members 22 of the handle 1 by means of a pin 24 at one end, and is pivoted within the U-shaped terminus 6 of the handle 2 at the other end by means of a pivot pin 25. As a result of this construction, separation of the handles 1 and 2 tends to break the toggle linkage and thereby swing the jaw 16 about the pin 14 in a clockwise direction, and squeezing of the handles together effects a reverse rotation of the jaw 16 about the pivot pin 14.

Suitable means are provided to break the toggle linkage and thus maintain the handles 1 and 2 in a separated position. In the preferred form of the invention illustrated, this means comprises a link 26, which is pivoted by means of a pin 27 between the side walls 22 of the handle 1 and a helical spring 28, one end of which is secured in an opening 29 in the extremity of the handle 1 and the other in an opening 30 in the link 26. The arrangement is such that the spring 28 normally tends to swing the link 26 in a counterclockwise direction about the pin 27, as viewed in Figure 1, thus tending to break the toggle linkage. The link is provided with a pair of grooves 31 in order to provide clearance between the link and the side walls 22 for the end of the spring 28.

The toggle breaking movement effected by the spring 28 and link 26 is limited to a relatively small angle by means of an abutment surface 32 formed on the left-hand extremity of the link 23 and adapted to abut the underside of the top wall of the handle 1 when the parts are in their fully opened position, illustrated in Figure 1. In that position, a flattened end portion 33 on the link 26 bears against the top surface of the link 23. This flattened surface is so arranged that the link extends at a small angle from a normal to the top surface of the link 23. This angle slightly exceeds the angle of repose for the materials of the link 26 and lever 23, with the result that upon application of a closing force to the handle 1, the end of the link 26 will tend to slide to the left, as viewed in Figure 1, along the top surface of lever 23. The spring 28 is a relatively light spring which resists this movement. The arrangement is such that an appreciable closing force must be applied to the handles before the link 26 will slip to the left, but as soon as such movement is started, the link 26 will swing to the position shown in Figure 2 and the resistance to closure of the handles induced by the spring 28 will be reduced to a negligible value by reason of

the fact that the line of force exerted by the spring approaches closely to the axis of pin 27. In the fully straightened toggle position illustrated in Figure 2, a nose 34 on the link 26 engages the underside of the top wall of the handle 1 to limit the toggle straightening action.

If, as is preferred in the operation of a wrench, it is desired to have the jaws release automatically when the pressure on the handles is relieved, the 10 nose 34 is so constructed that it stops the toggle straightening movement just short of the fully straightened position.

The wrench also incorporates means to swing the upper jaw in a counterclockwise direction about pin 21 to a limited extent sufficient to effect disengagement of the teeth 11 and 13. In addition, means are provided to urge the upper jaw 16 upwardly, as viewed in Figure 1, in order to maintain the jaws in a normally open position.

20 In the preferred form of the invention illustrated, both of these functions are performed by a single mechanism comprising a lever 35 and a helical spring 36, best shown in Figure 1. One end of the lever 35 is pivoted on a pin 37 carried by a pair of ears 38 formed on the flange 5 of the handle portion 2, as best shown in Figures 1 and 5. The opposite extremity of the lever 35 is twisted at 39 through an angle of 90° with respect to the plane of the lever and is provided with a 25 pair of oppositely projecting lugs 40 which project into slots 41 formed in the side plates 17 of the upper jaw 16, in the manner best shown in Figure 2. The slots 41 extend at an angle of approximately 45° with respect to the plane of the 30 jaw faces and, consequently, the force exerted upon the top walls of the slots 41 by the lugs 40 is in a direction to not only separate the jaws but to cause a rotation of the upper jaw in a counterclockwise direction about the pin 21 when the 35 lever 35 is urged in a clockwise direction about its pivot pin 37. One end of the spring 36 is fixed in an opening 42 in the thinner web section 8 and the opposite end in an opening 43 formed in the lever 35 adjacent its outer extremity, thus tending to swing the lever 35 in a direction to separate the jaws and at the same time to separate the teeth 11 and 13.

As a result of the above described mechanism, the wrench normally occupies the fully open position illustrated in Figure 1, with the toggle linkage broken to the full extent permitted by the limiting abutment 32. When it is desired to clamp the wrench on a nut, the jaws are placed over the nut in the usual manner and the handles 1 and 2 squeezed together by a single hand pressure. The arrangement of the levers 26 and 35 and the springs 28 and 36 is such that a pressure applied by the hand to the handles sufficient to overcome the force exerted by lever 35 will 50 close the jaws of the wrench on the nut without overcoming the tendency of the lever 26 and spring 28 to maintain the toggle linkage in its fully broken position. As a result, the toggle linkage, comprising the link 23, and the handle 1 pivot bodily about the pin 25 to close the jaws on a nut.

During such movement, the force exerted by the lugs 40 of lever 35 on the upper jaw 16 holds the pawl 12 out of contact with the teeth 11 and 70 the pawl rides along the smooth back wall 44 of the opening 9 without any straightening of the toggle linkage. As soon as the jaw 16 engages the nut, its bodily movement toward the jaw 3 will be arrested and continued pressure on the handles will tend to move the pivot pin 21 down-

wardly while the jaw fulcrums to a limited extent about its point of contact with the nut. This rocks the jaw in a clockwise direction about pin 21 simultaneously with the downward movement of the pin 21, thereby moving the pawl 12 downward and to the left, as viewed in Figures 1 and 2, until the teeth 13 engage the teeth 11. After the teeth have engaged, pin 21 can no longer move downwardly and, consequently, application of further pressure to the handles will cause link 26 to slip to the left along the top surface of lever 23 and the toggle links will be straightened. This straightening action will rock jaw 16 in a counterclockwise direction about pin 14 to a limited extent and thus apply a strong clamping action to the nut located between the jaws.

It is desirable to limit the force required to effect a closure of the jaws on a nut and, consequently, the lever 35 and spring 36 are so constructed that they exert the minimum jaw opening force necessary. Moreover, the arrangement of the spring 36 and the lever 35 is such that as the spring is stretched incident to closure of the jaws, the lever arm through which the spring force acts upon lever 35 decreases, with the result that the torque applied to the lever 35 is substantially constant in all positions of the lever. Lever 26 and spring 28 are then so constructed that they will maintain the toggle linkage broken when subject to a force sufficient to close the jaws, but will permit toggle straightening action on a slight increase in that pressure.

The construction, location and arrangement of the ratchet holding mechanism is such as to provide maximum holding strength and maintenance of the jaws of the wrench so nearly parallel at all times that the minute departures from true parallelism, which result from the limited swinging movements of the jaw 16, are more than compensated for by the toggle clamping action of the jaw on a nut. These results flow from a number of specific features of the wrench construction. Thus, in the preferred construction the teeth 11 and 13 are made as small as it is possible to manufacture them practically and still maintain a high degree of accuracy in tooth form and spacing. As a specific example, for a wrench of high quality and accuracy, the tooth spacing may be made as small as twenty-five one thousandths of an inch. As a result of the small size of the teeth, it is necessary to distribute the very high loads which they must carry over a relatively large number of teeth, as indicated on an enlarged scale in Figure 7. Moreover, it is necessary that all of the teeth on the pawl 12 make full depth engagement with the teeth 11 in order to properly and accurately distribute the load. An equal distribution of the load over all the teeth is achieved by pivoting the pawl 12 about the axis of pin 14 and by so arranging the parts that the resultant force transmitted from the pin 14 through the pawl 12 to the teeth 11 passes through teeth of pawl 12 intermediate the ends of the toothed surface of the pawl, as indicated by the dotted line arrow 45 in Figure 7. The direction of this force is such that the pawl will swing automatically about the axis of pin 14 until all of the teeth 13 on the pawl 12 seat squarely against the teeth 11.

It will be noted that the direction of the resultant force applied to the ratchet teeth, as indicated by the line 45, is an angle of approximately 45° to the faces of the jaws. This results from the relative positions of the axes of pins 14 and 21 relative to the face of jaw 16. Thus,

as shown in Figure 2, when the wrench is clamped upon an object, the toggle linkage will exert a force indicated by the dotted line arrow 46 on the jaw 16, while the object which is clamped 5 will exert a vertically acting force on the face of the jaw 16. The location of this latter force may be at any point along the length of the jaw face but, under the worst condition that may arise, will be concentrated at the innermost portion of the face, as indicated by dotted arrow 47. Since the distance from the innermost portion 10 of the face of jaw 16 to the line connecting the axes of pins 14 and 21 is approximately equal to the distance between the axes of pins 14 and 21, the resultant of the forces indicated by arrows 46 and 47 extends at an angle of 45° to the jaw faces, as indicated by dotted line arrow 45. If the load applied to the jaw 16 is located further 20 out on the jaw, the resultant of forces 46 and 47 will extend at an angle slightly less than 45° with respect to the jaw faces but will not depart from the 45° angle by an amount sufficient to cause cocking of the pawl 12.

By so locating the points of application of the 25 forces on the upper jaw that the resultant force on the pivot pin 14 extends at an angle of approximately 45° to the faces of the jaws, it is possible to construct the teeth 11 with side faces which make an angle of 45° with respect to the jaw faces and which, consequently, make an angle of 90° with each other, as shown in Figure 8. That form of tooth may be used without danger of slippage between the pawl and the teeth 35 11 by reason of the fact that the direction of the force 45 is approximately normal to the under sides of the teeth 11 under the worst possible conditions. A major advantage of teeth so formed 40 is that they provide the maximum strength because the loads applied to them are pure compression loads, thus eliminating all bending and shearing stresses on the teeth.

In order to utilize the full load carrying capacity of teeth 11 and 13, it is not only necessary to provide the automatic self-aligning pawl construction previously described, but it is also necessary to insure that teeth 13 engage to the full depth of the teeth 11 at all times. Such full depth engagement is positively insured in the illustrated embodiment of the invention by reason of the fact that the path of movement of the points of the teeth 13, as they approach the teeth 11, is in such a direction that initial contact between the teeth 11 and 13 will occur at the upper sides of the teeth 11, while in the final position the load is taken by the lower sides of the teeth 11. As a result, straightening of the toggle linkage causes the teeth 13 to slide up the upper surfaces of teeth 11 into full depth engagement. Initial engagement at the upper sides of teeth 60 11 always occurs because pins 14 and 21 are moving downwardly during the limited rocking movement of the jaw 16, which occurs after it engages an object located between the jaws and before the toggle linkage is straightened. Thus 65 the points of the teeth 13 have a resultant movement parallel to the path indicated by dotted line 48 in Figure 9.

The location of the line 48 extending between any pair of engaging teeth will depend upon the thickness of the object engaged by the jaws. For certain thicknesses of objects, it is theoretically possible to have the points of teeth 13 make initial contact exactly with the points of teeth 11. That condition, which is illustrated in Figure 8, 70 75 is the worst condition that can arise because in

such case the final engagement may occur one-half a tooth space above or below the point of initial contact for a negligible variation in the size of the object clamped. This variation in position of the dog is compensated for by the swinging of jaw 16 about pin 14 incident to operation of the toggle linkage. However, to obtain maximum mechanical advantage and minimum departure from parallelism, this swinging movement should be as small as possible and, therefore, the teeth should be as small as practicable. Even where initial engagement of the teeth occurs point to point, final engagement will be to full tooth depth because if the points of the teeth catch during movement of teeth 13 along the line 48, the subsequent change in the direction of the forces caused by straightening the toggle links will cause the points of teeth 13 to slide inwardly on the upper sides of teeth 11.

Another factor affecting the degree to which the jaws remain parallel in clamping position and the amount of movement which the toggle linkage must transmit to pin 21 is the width of the opening 9 as compared with the size of the pawl 12. The clearance between the pawl and wall 44 in Figure 7 determines the extent of swinging movement of the jaw 16 about the pin 21. This clearance should be as small as possible. However, it must be sufficient to permit complete disengagement of the teeth 11 and 13 and also permit such further separation as is necessary to prevent engagement of the point of pawl 12 with the teeth 11 due to the limited possible cocking movement of the pawl during separation of the jaws. The tooth depth determines the amount of movement required for separation, and the tooth spacing determines the amount of swinging movement of the jaw 16 which is necessary to effect clamping of an object whose dimensions do not correspond to any possible adjustment of the pawl 12 along the teeth 11. Consequently, if, as is preferred, the teeth are made quite small, very little swinging movement of the jaw about pin 14 is necessary to clamp tightly on any size object and, therefore, very little pivotal movement of the pawl 12 with reference to the side plates 17 is required to insure distribution of the load over all of the teeth 13. It is for that reason that the flat surfaces 18 of the openings in the side plates 17 are designed to limit swinging movement of the pawl 12 with respect to the side plates.

It will be noted that the maintenance of parallelism of the jaws during adjustments of the wrench results from the form and location of teeth 13 with respect to the toggle linkage. So long as the paths of movement of the pins 14 and 21 are in substantially the same line or are in substantially parallel lines, the faces of the jaws will remain substantially parallel. In the preferred construction, the points of the teeth 11, instead of lying in a flat plane, lie in a plane which is curved with a radius equal to the length of the toggle linkage made up of handle 1 and link 23; and the center of this radius is located at the point indicated by the numeral 49, which is the same distance from the axis of pin 25 as the distance separating the axes of pins 14 and 21. The back wall of the opening 9 is also preferably curved about the same center and the points of the teeth 13 on the pawl 12 are located on a similar convex curve so that they will properly mate with the teeth 11. To further minimize deviations from parallelism, the face of jaw 16 should extend at such an angle that it is

parallel to the face of jaw 3 when the toggle linkage is fully broken and the points of the teeth 13 on pawl 12 have advanced until they are in the same plane as the points of the teeth 11. 5 Then, as the pawl teeth 13 complete their inward meshing movement, the jaw 16 will swing open slightly and the subsequent toggle straightening operation will tend to return them to the closed parallel position.

10 The wrench mechanism described above will automatically release upon relief of the handle squeezing pressure, and the jaws will open to permit ratcheting of the wrench about the nut for a new grip. For some purposes, however, it 15 is desirable to have a wrench which will act as a clamp and hold itself in locked position upon an object. Accordingly, in Figures 9 and 10 is illustrated a modified form of the invention incorporating means for that purpose. The 20 wrench illustrated fragmentarily in Figures 9 and 10 is identical in construction and mode of operation to the preferred embodiment previously described except that the lever 50, which corresponds to the lever 26 of the previous embodiment, has a nose portion 51 which will permit the 25 toggle linkage to swing slightly past its dead center or straightened position when the heel of the lever is engaging the top surface of the lever 23. As a result, the wrench will maintain itself 30 in a clamped condition on any object until a positive separating force is applied to the handles.

A relatively thin sheet metal sleeve 52 surrounds and is slidable upon the lever 23. When 35 it is desired to use the tool in the usual manner as a wrench which will release automatically, the sleeve 52 is slid into the position illustrated in Figure 9, in which it is interposed between the heel of lever 50 and the top surface of lever 23. 40 The thickness of the sleeve 52 is sufficient to prevent complete straightening of the toggle linkage and, consequently, upon release of the handles, the wrench will automatically open. Sleeve 52 may be slid to the right, as viewed in Figure 9, to a position in which it does not contact the lever 50, in which event the tool is self-locking.

It will be observed that there is provided, in accordance with the present invention, an automatically adjustable parallel jaw wrench which, 50 by a single squeezing movement of the handles, will close freely on any size object and then apply a clamping force having exceedingly high mechanical advantage, regardless of the size of the object clamped. The initial adjusting movement prior to engagement of the object is made 55 without any mechanical advantage and, consequently, the force multiplying mechanism need only operate through the small final clamping movement. The construction is such that the force multiplying mechanism makes no appreciable movement until after the jaws have closed on the object. As a result, an exceedingly high degree of force multiplication may be provided without limiting the over-all range of adjustment.

60 65 70 While the wrench employs a ratchet holding mechanism, that mechanism is of such construction that an effective clamping action is achieved on objects the size of which fall intermediate the increments of the ratchet mechanism. Consequently, the wrench is, in effect, adjustable to any infinitesimal variation in the size of the work-piece. Moreover, by making the ratchet teeth exceedingly small, the final clamping action may be effected without any appreciable departure of the jaws from absolute parallelism. In fact, due

to the heavy clamping of the jaws on the object, a slight departure from parallelism which may exist in certain cases will produce less angle between the faces of the jaws and the faces of a nut than will the normal clearance provided in prior fixed wrenches.

Another important feature of the wrench resides in the fact that all of the heavy stresses to which the various elements of the wrench are subject are directly applied tension or compression stresses, with the result that distortion and flexure, which would otherwise be encountered if any of the elements were subject to bending stresses, are avoided. Moreover, since the toggle mechanism pre-loads the wrench by clamping the nut, no spreading or distortion of the wrench jaws will occur on twisting a nut until the force at the nut corners due to the twisting action exceeds the clamping force. The ratchet mechanism is peculiarly designed to provide maximum load capacity. Moreover, the construction is such that there is no danger of stripping the teeth of the ratchet mechanism; and, since during idle adjusting movements the ratchet teeth are held out of engagement by spring 36 and lever 35, there is no possibility of the points of the teeth being worn away or rounding off by relative sliding engagement.

Another feature of the wrench resides in the fact that the adjustment for different sizes of nuts is effected by bodily swinging movements of the toggle linkage including the handle 1 about the pivot 25 at the rear end of handle 2. Consequently, such adjustments do not have any appreciable effect upon the spacing of the rear ends of the handles and it is thus possible to space the handles at the optimum distance for a normal hand grip.

It will be apparent that variations in the design and construction may be indulged in without departing from the spirit of the invention. Thus the size of the teeth 11 and 13 may be varied, depending upon the degree of parallelism required in the wrench. Moreover, since the length of the opening 9 is relatively short compared to the length of the toggle linkage, the points of the teeth 11 may lie in a flat plane parallel to the direction of movement of the movable jaw without serious departure from parallelism of the jaws. The particular wrench illustrated is so constructed that the jaws will not close into contact with each other and hence is adapted for use on a range of nut sizes, from a maximum size which will fit the spacing of the jaws illustrated in Figure 1 to a minimum size which will fit the spacing illustrated in Figure 2. If so desired, the wrench may be so constructed by simply altering the shape of the jaws that the jaw faces contact each other when the remaining parts are in the position shown in Figure 2. Such a wrench would then operate on smaller range of sizes.

While the use of combined levers and springs for maintaining the toggle broken, the jaws open and the ratchet teeth out of contact provide optimum performance, it will be apparent that the jaws may be maintained broken by a single leaf spring and the jaw movements controlled by either one or two springs without using either of the levers 26 and 35.

Other variations in the design and construction will be obvious to those skilled in the art and may be indulged in without departing from the spirit of the invention or the scope of the appended claims.

What is claimed is:

1. A wrench having a pair of handles adapted to be gripped in one hand, a jaw carried by one of said handles, an element mounted for sliding movement with respect to said jaw in a direction approximately at right angles to the face of said jaw, a second jaw pivoted on said element, a pair of interconnected links forming a toggle linkage one of which links is pivoted to the second jaw and the other to said one handle, resilient means connected to the toggle linkage and normally acting to break the toggle linkage, the other handle being connected to the toggle linkage with the result that a squeezing of said handles together tends to bring the toggle linkage pivots into alignment and to swing said linkage bodily about its connection to the first handle in a direction to close the jaws, the location of the points of connection of said toggle linkage to said second jaw and said one handle being such that the faces of said jaws remain substantially parallel as said element slides with respect to said one jaw, said one jaw having a plurality of teeth fixed thereto and extending alongside the path of movement of said element, cooperating ratchet teeth on said element, a second resilient means connected to the second jaw and normally urging said teeth out of engagement by limited pivotal movement of the second jaw about its connection to the toggle linkage, the teeth on said one jaw and the face on the other jaw facing in the same direction around the axis of the pivotal connection between the toggle linkage and the other jaw, with the result that engagement by the second jaw with an object located between the jaws when said handles are squeezed together will swing said second jaw about its connection to the toggle linkage in a direction to cause engagement of said teeth and against the force exerted by the second resilient means, and the strength of said first resilient means relative to the strength of said second resilient means being such that squeezing of said handles together will cause engagement of said ratchet teeth before the toggle linkage begins to straighten.

2. A wrench having a fixed jaw, a movable jaw connected to the fixed jaw for pivotal and slideable movement with respect thereto, a toggle linkage connecting the movable jaw to the fixed jaw and extending at approximate right angles to the direction of relative sliding movement between said jaws, said toggle linkage including a handle member the major hand-engaging portion of which is positioned between the points of connection of the linkage to the two jaws with the result that hand pressure applied to the handle tends to slide the jaws toward each other, means for holding said jaws against relative sliding movement in any one of a plurality of positions of adjustment to permit clamping of an object by straightening of said toggle linkage and pivotal movement of the movable jaw, and resilient means for resisting straightening of said toggle linkage in order to permit pressure exerted on said handle to slide the movable jaw toward the fixed jaw prior to engagement of an object between said jaws without straightening of said toggle linkage.

3. A wrench having a pair of handles adapted to be gripped by one hand, a jaw fixed to one handle, a second jaw pivotally connected to the other handle, a link pivotally connected at one end to said one handle at a fixed point thereon and at the other end to the second handle intermediate its ends and forming with said other

handle a toggle linkage, an element connected to said one handle for sliding movement in a direction intersecting the plane of the face of the first jaw and in a path lying approximately on an arc of a circle having a radius equal to the length of the straightened toggle linkage and having its center spaced from said fixed point by a distance equal to the distance between the pivotal connections between the second jaw and said other handle and said element, and a pivotal connection between the element and the second jaw, said one handle and said element having interengaging surfaces thereon for holding said element in any one of a plurality of positions with respect to said one handle.

4. A wrench having a pair of jaws, an element connected to one jaw for sliding movement relative to said jaw in a path approximately at right angles to the plane of the jaw face, a pivotal connection between said element and the other jaw, a series of teeth on said one jaw which extend alongside the path of movement of said element, said teeth pointing toward said element, co-operating teeth on said element adapted to mesh with said first series of teeth, and a link mechanism pivotally connected to and between said jaws and extending approximately at right angles to the path of sliding movement of said element and co-operating with said element to guide said other jaw for movement toward and from the one jaw and maintain the jaw faces substantially parallel, the pivotal connection between said link mechanism and said other jaw being spaced from the pivotal connection between said element and said other jaw, the teeth on said one jaw and the face on the other jaw facing in the same direction around the axis of the pivotal connection between said other jaw and said link mechanism so that a force applied perpendicularly to the face of said other jaw will swing said other jaw about its pivotal connection to said link mechanism in a direction to cause meshing of said teeth on the element with those on said one jaw.

5. A wrench having a pair of jaws, an element connected to one jaw for sliding movement relative to said jaw in a path approximately at right angles to the planes of the jaw face, a pivotal connection between said element and the other jaw, a series of teeth on said one jaw which extend alongside the path of movement of said element, said teeth pointing toward said element, co-operating teeth on said element adapted to mesh with said first series of teeth, a link mechanism pivotally connected to and between said jaws and extending approximately at right angles to the path of sliding movement of said element and co-operating with said element to guide said other jaw for movement toward and from the one jaw and maintain the jaw faces substantially parallel, the pivotal connection between said link mechanism and said other jaw being spaced from the pivotal connection between said element and said other jaw, the teeth on said one jaw and the face on the other jaw facing in the same direction around the axis of the pivotal connection between said other jaw and said link mechanism so that a force applied perpendicularly to the face of said other jaw will swing said other jaw about its pivotal connection to said link mechanism in a direction to cause meshing of said teeth on the element with those on said one jaw, and a single resilient means constantly urging said other jaw in a direction to separate said jaws and also rotate

said other jaw about its pivotal connection to said link mechanism in a direction to cause separation of said ratchet teeth so that engagement between said teeth will not occur until a force is applied to the face of said other jaw.

6. A wrench having a pair of jaws, an element connected to one jaw for sliding movement relative to said jaw in a path approximately at right angles to the planes of the jaw face, a pivotal connection between said element and the other jaw, a series of teeth on said one jaw which extend alongside the path of movement of said element, said teeth pointing toward said element, co-operating teeth on said element adapted to mesh with said first series of teeth, a link mechanism pivotally connected to and between said jaws and extending approximately at right angles to the path of sliding movement of said element and co-operating with said element to guide said other jaw for movement toward and from the one jaw and maintain the jaw faces substantially parallel, the teeth on said one jaw and the face on the other jaw facing in the same direction around the axis of the pivotal connection between said other jaw and said link mechanism so that a force applied perpendicularly to the face of said other jaw will swing said other jaw about its pivotal connection to said link mechanism in a direction to cause meshing of said teeth on the element with those on said one jaw, and resilient means constantly urging said element out of contact with said teeth so that engagement between said teeth will not occur until after a force is applied to the face of said other jaw, said link mechanism including means for pivoting said other jaw about its pivotal connection to said element to apply a clamping force to an object between said jaws after said teeth have engaged.

7. A wrench having a pair of handles adapted to be gripped in one hand, a jaw carried by one of said handles, an element mounted for sliding movement with respect to said jaw in a direction approximately at right angles to the face of said jaw, a second jaw pivoted on said element, a pair of interconnected links forming a toggle linkage one of which links is pivoted to the second jaw and the other to said one handle, resilient means normally acting to break the toggle linkage to a limited degree so that the linkage will swing as a unit about the pivotal connection to the handle, the other handle being associated with the toggle linkage in such a manner that a squeezing of said handles together tends to bring the toggle linkage pivots into alignment and to swing said linkage bodily about its connection to the first handle in a direction to close the jaws, the location of the points of connection of said toggle linkage to said second jaw and said one handle being such that the faces of said jaws remain substantially parallel as said element slides with respect to said one jaw, said one jaw having a plurality of teeth fixed thereto and extending alongside the path of movement of said element, co-operating teeth on said element, a second resilient means normally urging said teeth out of engagement by limited pivotal movement of the second jaw about its connection to the toggle linkage, the teeth on said one jaw and the face on the other jaw facing in the same direction around the axis of the pivotal connection between the toggle linkage and the other jaw, with the result that engagement by the second jaw with an object located between the jaws when said handles are squeezed together will swing said second jaw about its connection to

the toggle linkage in a direction to cause engagement of said teeth and against the force exerted by the second resilient means, and the strength of said first resilient means relative to the strength of said second resilient means being such that squeezing of said handles together will cause engagement of said teeth before the pivots of said toggle linkage are aligned.

8. A wrench having a pair of handles, a wrench jaw fixed on one handle at one extremity thereof with its jaw face extending approximately parallel to the length of the handle, a link pivotally connected at one end of the other handle and at its opposite end to the opposite extremity of said one handle and forming with said handle a toggle linkage, a member connected to said jaw for movement relative thereto in a direction approximately at right angles to the plane of the face of said jaw, a second jaw pivotally connected at spaced points to said other handle and said member whereby bodily pivotal movement of said toggle linkage about the axis of its connection to the first handle and toward the first handle will cause said jaws to approach each other, resilient means tending to separate said jaws, means to lock said member against movement relative to said first jaw, and means to resist relative pivotal movement between said handle and link in order to induce said bodily pivotal movement of said toggle linkage when one handle is forced toward the other.

9. A wrench having a fixed jaw, a movable jaw connected to the fixed jaw for pivotal and slidable movement with respect thereto, a toggle linkage connecting the movable jaw to the fixed jaw and extending at approximate right angles to the direction of relative sliding movement between said jaws, said toggle linkage including a handle member the major hand-engaging portion of which is positioned between the points of connection of the linkage to the two jaws with the result that hand pressure applied to the handle tends to slide the jaws toward each other, means for holding said jaws against relative sliding movement in any one of a plurality of positions of adjustment to permit clamping of an object by straightening of said toggle linkage and pivotal movement of the movable jaw, and resilient means for resisting straightening of said toggle linkage in order to permit pressure exerted on said handle to slide the movable jaw toward the fixed jaw prior to engagement of an object between said jaws without straightening of said toggle linkage, said last mentioned means including a lever pivoted on one of the links and having a sliding engagement with the other link and acting as a strut to resist movement of the pivot point toward the other link, the line between the axis of the lever pivot and the point of contact between the lever and said other link lying at an acute angle to the contacted link surface which decreases when the lever slides along said other link incident to straightening of the toggle linkage, and a spring acting between the lever and one of said links for exerting a force tending to rotate said lever in a direction to increase said angle.

10. A wrench having a fixed jaw, a movable jaw connected to the fixed jaw for pivotal and slidable movement with respect thereto, a toggle linkage connecting the movable jaw to the fixed jaw and extending at approximate right angles to the direction of relative sliding movement between said jaws, said toggle linkage including a handle member the major hand-engaging por-

tion of which is positioned between the points of connection of the linkage to the two jaws with the result that hand pressure applied to the handle tends to slide the jaws toward each other, means for holding said jaws against relative sliding movement in any one of a plurality of positions of adjustment to permit clamping of an object by straightening of said toggle linkage and pivotal movement of the movable jaw, and resilient means for resisting straightening of said toggle linkage in order to permit pressure exerted on said handle to slide the movable jaw toward the fixed jaw prior to engagement of an object between said jaws without straightening of said toggle linkage, said last mentioned means including a lever pivoted on one of the links and having a sliding engagement with the other link and acting as a strut to resist movement of the pivot point toward the other link, the line between the axis of the lever pivot and the point of contact between the lever and said other link lying at an acute angle to the contacted link surface which decreases when the lever slides along said other link incident to straightening of the toggle linkage, and a spring acting between the lever and one of said links for exerting a force tending to rotate said lever in a direction to increase said angle, the angle between the line of force exerted by the spring on the lever and said line between the lever pivot and point of contact being such that the effective lever arm of the spring force on the lever reduces as the toggle linkage is straightened, said lever having a portion which acts as a positive abutment between said handle and other link to prevent said toggle linkage from breaking in one direction.

11. A wrench having a pair of generally parallel handles adapted to be gripped by one hand, a jaw fixed on the forward end of one handle, a second jaw mounted for sliding movement relative to the first jaw in a direction approximately at right angles to said handles, a pivotal connection between the forward end of the other handle and the second jaw with the result that when the forward ends of said handles are squeezed toward each other the jaws are caused to approach and when the rearward ends of the handles are moved toward each other the other handle pivots around its connection to the second jaw, automatic means operable in response to engagement of said jaws on an object for holding said jaws against relative sliding movement, yielding means connected to the other handle for resisting movement of the rear ends of the handles toward each other, separate yielding means connected to the jaws for separating the jaws, and force multiplying means connected to said other handle and operable when the rear ends of said handles are moved toward each other to force said jaws toward each other while the reaction force is sustained by said automatic means.

12. A wrench having a fixed jaw, a movable jaw connected thereto, a pair of handles connected to said jaws for moving the jaws toward each other, a lever pivoted to one jaw and engaging the other, and a spring connected to the lever and to said one jaw and exerting a force tending to swing said lever in a direction to separate said jaws, the angle between the line of the force exerted by the spring on the lever and a line through the point of connection between the spring and lever and the pivotal axis of the lever being an acute angle which increases as the lever swings in a direction to separate the jaws with

the result that the effective lever arm of the spring force on the lever reduces in approximate proportion to the increase in the force applied by the spring to the lever as the jaws move toward each other.
